Primary Examiner — Cynthia Underwood*(74) Attorney, Agent, or Firm* — John A. Doninger(57) **CLAIM**

The ornamental design for a serving dish with cover, as shown and described.

DESCRIPTION

FIG. 1 is a top, side and front perspective view of the first embodiment of a serving dish with cover showing my new design;

FIG. 2 is a front elevation view, the rear elevation being a mirror image thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines are included for illustrative purposes only and form no part of the claim.
